UNITED STATES PATENT OFFICE.

THOMAS CHARLES CROUCH, OF SASKATOON, SASKATCHEWAN, CANADA.

AUTOMOBILE-HEATER.

1,219,924.

Specification of Letters Patent. Patented Mar. 20, 1917.

Application filed September 15, 1916. Serial No. 120,241.

To all whom it may concern:

Be it known that I, THOMAS C. CROUCH, a subject of the King of Great Britain, and a resident of Saskatoon, in the Province of 5 Saskatchewan and Dominion of Canada, have invented a certain new and useful Improvement in Automobile-Heaters, of which the following is a specification.

This invention is an improvement in heaters, and has particular reference to a heater for automobiles controlled by the exhaust from the engine.

An object of the invention is the provision of a heater casing adjustably mounted 15 upon a suitable support in a vehicle, whereby the same may be moved to a position preferably beneath a seat and also adjusted in such a manner as to be employed as a foot warmer.

20 Another object is to provide a heater casing wherein a system of heating pipes is connected to the exhaust of the engine and the flow of burnt gases through said pipes regulated by a novel valve mechanism controlled by the operator.

25 The inventive idea involved is capable of receiving a variety of mechanical expressions, one of which for the purpose of illustrating the invention is shown in the accompanying drawings, wherein:—

Figure 1 is a perspective view of the heater, showing the same applied to a vehicle;

Fig. 2 is a similar view showing the valves 35 for controlling the flow of the exhaust from the exhaust pipe to the heater casing;

Fig. 3 is an end elevation of this mechanism;

Fig. 4 is a longitudinal section taken 40 through the heater casing; and

Fig. 5 is a section on the line 5—5 of Fig. 4.

The invention is illustrated in connection with a vehicle 6 having the usual floor 7 45 and seat 8. Mounted below the floor 7 in the usual manner is the exhaust pipe 9 leading from the engine to the muffler 10.

There is shown what is now believed to be a preferred form of the invention, consisting 50 of a heater casing 11 preferably made of metal and of substantially rectangular formation. The interior of the casing 11 is provided with a lining of asbestos 12, which lining serves the double purpose of 55 retaining the heat and also as a precaution, against excessive heat. Formed in the lin-

ing 12 are a plurality of spaced heat outlet chambers 13 having suitable covering 14, said chambers having an outlet on one side of the casing 11. For the purpose of regulating the amount of heat coming from the chambers 13, there is preferably provided a slide member 15 extending longitudinally of the casing 11 and mounted in the guide flanges 16 formed thereon. This slide member is provided in its front with a plurality of openings 17 corresponding in number to the number of chambers 13 and said openings are adapted to register with the outlets of said chambers in order to permit of the heat in the heater casing making its exit therefrom. The member 15 is provided with a knob or handle 18, which may be grasped by the operator in order to adjust said member back and forth in order to regulate the size of the heat exit openings.

As shown in Fig. 1, one of the adjusted positions of the heater casing is beneath the seat 8 of the vehicle and said casing is retained in this position by means of the straps 19 or other holding devices, which are hinged at 20 to the floor 7 of said vehicle. By hinging the casing 11 through the medium of the straps 19, it is readily apparent that the said casing may be swung from vertical to horizontal position whereupon the heater may be used as a foot warmer.

In order to circulate the exhaust gases through the heater casing, the exhaust pipe 9 is tapped at 21 for the reception of a branch pipe 22, which has the inlet end 23 of the circulating pipe 24 mounted therein. This circulating pipe 24 is preferably made in sections and extends through the asbestos lining 12 and around the several chambers 13, as best illustrated in Fig. 4, and the outlet end 25 of said pipe terminates adjacent the inlet end 23. The pipe 24 is provided with a branch pipe 26 which extends longitudinally of the heater casing and 100 through the several chambers 13. To allow for the adjustments of the heater chamber from vertical to horizontal positions and vice versa, the circulating pipe 24 is provided adjacent its inlet and outlet ends with 105 the universal coupling 27, shown in section in Fig. 5. The openings 28 in the casing 11 through which the inlet and outlet ends of the pipe 24 extend are elongated, as shown in Fig. 1 to permit of said adjustments. It will thus be seen that should it be desired to move the heater casing from

one position to another, this operation may be readily and quickly accomplished.

The mechanism for controlling the flow of exhaust gases through the circulating pipe 24 preferably comprises a valve 29 pivotally mounted in the exhaust pipe 9 and normally in an opened position. Another valve 30 is likewise pivotally mounted in the branch pipe 22 and is normally in closed position. An angular bracket 31 is secured upon the top of the exhaust pipe 9, and has pivoted to a free extremity thereof a double bell-crank lever 32, having two of its arms bifurcated at the ends as indicated at 33, one 10 of the bifurcations receiving an arm 34 which actuates the valve 29, while the other bifurcation receives a pin extension 35 carried by an arm 36 which operates the valve 30 about its pivot. Connected to the extremity of the third arm of the bell-crank lever 32 is one end of a flexible connection 37, which passes over a pulley 38 and extends to a point in the vehicle readily accessible by the operator. A spring 39 secured to the 25 bell crank lever and to the arm 31 holds the valves 29 and 30 in normal position. It will be seen from this description that by exerting a pull upon the connection 37, the valves 29 and 30 will be respectively closed and 30 opened, and the exhaust gases will be shunted through the circulating pipe 24 in the heater casing. When the connection 37 is released the valves are returned to normal position by the spring 39.

35 I claim:

1. A vehicle heater comprising a casing, supporting means for the casing embodying hinged joints to admit of the casing having a swinging movement and a heat circulating pipe embodying a fixed portion and a portion housed within the casing, the two 40 portions of the heat circulating pipe being connected by means of universal couplings to admit of swinging movements of the heater.

2. In a vehicle, the combination of a heater casing, a heat retaining lining in said casing and having a plurality of spaced heat outlet chambers, means leading from the exhaust pipe of the engine and surrounding said chambers for circulating the 50 burnt gases from the exhaust pipe through said heater casing and adjustable means for regulating the size of the outlet openings 55 of said chambers.

3. In a vehicle, the combination of a heater casing, a heat retaining lining in said casing and having a plurality of spaced heat outlet chambers, means leading from the exhaust pipe of the engine and surrounding said chambers for circulating the burnt gases from the exhaust pipe through said heater casing, adjustable means for regulating the size of the outlet openings of said chambers, and valves in the exhaust 60 pipe of the engine and said circulating means and operated to permit of the passage of the burnt gases through the latter means.

4. In a vehicle, the combination of a heater casing, a heat retaining lining in said casing and having a plurality of spaced heat outlet chambers, means leading from the exhaust pipe of the engine and surrounding said chambers for circulating the 70 burnt gases from the exhaust pipe through said heater casing, adjustable means for regulating the size of the outlet openings of said chambers, valves in the exhaust pipe of the engine and said circulating means 75 and operated to permit of the passage of the burnt gases through the latter means, and means for pivotally mounting said heater casing upon the floor of the vehicle whereby the same may be adjusted to vertical and horizontal positions.

5. In a vehicle, the combination of a heater casing, a heat retaining lining in said casing and having a plurality of spaced heat outlet chambers, means leading from 90 the exhaust pipe of the engine and surrounding said chambers for circulating the burnt gases from the exhaust pipe through said heater casing, adjustable means for regulating the size of the outlet openings 95 of said chambers, valves in said exhaust pipe and said circulating means for controlling the passage of the burnt gases through said latter means, the valve in said exhaust pipe being normally opened, while the valve 100 in said circulating means is normally closed, and means for simultaneously operating said valves to close the exhaust pipe and to permit of the entrance of the exhaust gases into said circulating means.

THOMAS CHARLES CROUCH.
